UNITED STATES PATENT OFFICE

HOWARD E. WHITE, OF HOLDENVILLE, OKLAHOMA, ASSIGNOR OF ONE-HALF TO HARRY R. ALLEN, OF HOLDENVILLE, OKLAHOMA

DERRICK CONSTRUCTION

Application filed September 10, 1928. Serial No. 304,964.

The present invention relates to improvements in a metallic building structure and has reference more particularly to a derrick for use in drilling oil, gas, artesian wells, etc.

One of the important objects of the present invention is to provide a derrick construction wherein the parts thereof are so arranged as to permit the same to be readily and easily assembled or dismantled, without necessitating the installation or removal of a single bolt.

Still a further object is to provide a derrick construction of the above mentioned character, wherein the corner posts or uprights are formed of sections adapted to be arranged in superjacent relation, splice bar units being associated with the upper end of each section for cooperation with the adjacent lower end of the superposed section to facilitate proper assembly of the corner posts, when setting up the derrick for use, girts being arranged horizontally across the adjacent corner posts or uprights and brace rods further connecting the corner posts or uprights to properly support the derrick in its assembled position.

Still a further object is to provide a derrick construction wherein an improved pump assembly is provided for the derrick construction, said pump assembly being also of sectional formation to permit ready and easy putting together or taking apart of this portion of the derrick.

A further and salient object of the present invention is to provide a derrick construction of the above mentioned character which will save considerable expense, time and labor as it is well known that in drilling gas wells after the well has been drilled, it is unnecessary to leave the derrick permanently erected over the well and consequently after the derrick has served its purpose it can be quickly and easily dismantled and again set up for use over another well that is to be drilled.

Still a further object is to provide a derrick construction of the above mentioned character which is not only simple but inexpensive, and strong and durable, as well

as efficient and reliable in carrying out the purposes for which it is designed.

Other objects and advantages of the invention will become apparent as the nature of the invention proceeds and when taken in connection with the accompany drawings.

In the accompanying drawings:

Figure 1 is a side elevation of the derrick embodying my invention.

Figure 2 is a transverse section taken approximately on the line 2—2 of Figure 1, looking downwardly.

Figure 3 is a similar section taken substantially upon the line 3—3 of Figure 1.

Figure 4 is a detail view, showing the manner in which a girt is disposed when in its lowered position with respect to the adjacent corner posts or uprights.

Figure 5 is a similar view, showing one of the girts in the act of being forced downwardly by a special tool.

Figure 6 is a fragmentary perspective view of one of the sections of the corner posts or uprights looking at the outer side thereof.

Figure 7 is a detail perspective view of the upper end portion of one of the sections of the corner posts or uprights, looking from the inside.

Figure 8 is a detail sectional view, showing the manner in which the adjacent ends of one pair of sections of the corner posts are assembled together.

Figure 9 is a detail sectional view, showing the manner of assembling the cap structure on one of the corner posts.

Figure 10 is a fragmentary detail perspective view of one of the headers forming a part of the cap structure.

Figure 11 is a similar view of the complementary end portion of one of the side headers.

Figure 12 is a sectional view, taken approximately upon the line 12—12 of Figure 4.

Figure 13 is a sectional view, taken substantially on the line 13—13 of Figure 10, and

Figure 14 is a detail perspective view of one of the brace rods.

In the drawings, wherein for the purpose of illustration is shown the preferred embodiment of my invention, the numeral 1 designates generally my improved derrick the same comprising the upwardly converging corner posts or uprights 2, each of which is constructed of angle iron material and is furthermore of sectional formation, one of the sections being fragmentarily shown at 3 in Figure 6. The lowermost sections of the corner posts are secured to an appropriate base designated generally by the reference character 4, and in the present instance, the base consists of channeled bars 5 that are bolted to the respective corner posts as shown very clearly in Figure 1.

Sections 3 of each corner post or upright are arranged in longitudinal alignment with each other with their ends abutting and at the abutting portions of adjacent sections of each corner post, there is provided what I term an angular splice bar unit 6, for connecting the adjacent ends of the superjacent sections of the respective corner posts together.

Attention is now directed to Figures 6 and 7 of the drawings, wherein there is disclosed the specific construction of one of said splice bar units. A relatively large angular bracket 7 is secured against the outer face of the upper end portion of each section 3 and it will be observed that the side edges of the angular plate or bracket projects beyond the adjacent side edges of the angle iron sections, while the upper edges of the angular plate project above the upper edge of said section, and suitable notches 8 extend downwardly from the upper edges of the sides of the angular bracket or plate 7 and terminate at a point above the upper edges of the respective sides of the section 3, for a purpose to be presently described.

Angularly disposed slots 9 are formed in the upper corner portion of the angular bracket or plate 7 while secured to the outer face of each side of the angular plate or bracket are the flat strips 10, the same being spaced from the respective sides of the angular plate or bracket through the medium of spaced washers 11 that encircle the fastening rivets 12, and the purpose of this particular arrangement for construction will also be presently described.

A smaller angular bracket or plate 13 is secured on the inner face of the upper end portion of each section 3 in such a manner that the upper portion of this inner angular plate 13 projects above the upper edge of the section 3 as shown very clearly in Figures 7 and 8 of the drawings. Rivets or the like are employed for securing the inner and outer plates to the upper end of each angular section, and certain of these rivets denoted by the reference character 14 have their outer threaded ends spaced from the outer faces

of the angular bracket or plate 7, by suitable spacing sleeves, shown at 15, for a purpose also to be hereinafter more fully described. Relatively thin spacing members 19 are interposed between the inner angular brackets 7 or plates 13 and the adjacent sides of the upper end portion of each section 3.

An angular metallic bracket 16 is secured on the outer face of the lower end portion of each section 3 and as is clearly shown in Figure 6, the lower edge of each side of the angular bracket 16 is directed to provide a laterally disposed foot 17. The inner corners of the laterally disposed feet are cut away as illustrated at 18.

Suitable spacing elements are associated with the fastening rivets 20 to maintain the lower angular bracket 16 in spaced relation with respect to the outer face of the respective sides of the lower end portion of each section of each corner post or upright.

The invention further comprehends the provision of a particular girt construction for association with each pair of adjacent corner posts, and in Figures 4 and 5 of the drawings, there is shown in detail, the specific construction of one of the girts. The girt is formed of angle iron material and is designated by the reference character 21. These girts extend horizontally across the outer faces of each pair of opposed angle brackets 7. The vertical wall or side of each angle iron disc is formed at one end with the cut-away portion 23 and inwardly of this cut-away portion the vertical wall 22 of each girt 21 is formed with a slightly inclined notch 24, whereby to provide a finger 25, that is disposed between the spacing elements that encircle the rivets 12, it being understood that the vertical walls 22 of the angular girt 21 is disposed between the outer face of the angular bracket 27 and the adjacent strip 10, as is shown very clearly in the detail in Figure 12.

The other end of the vertical wall 22 of each girt is also cut away as at 26, and a notch 27 is formed at a point inwardly of the cut-away portion 27, whereby a finger 28 is formed between the cut-out portion 26 and the notch 27. The only difference between the finger 28 and the finger 25 is that the finger 25 has both of its side edges disposed at an incline whereas the finger 28 has only one edge disposed at an incline, and this particular edge forms one side of the notch 27.

The girts 21 are positioned horizontally across the sections of the adjacent corner posts and are installed subsequent to the erection of each series of sections.

In the erection of the derrick, the lowermost sections are initially secured to the channel bars 5 of the base 4, whereupon the lower ends of the superjacent sections fit between the spaced inner and outer angular plates 13 and 7 respectively, the notches 8 ac-

commodating the fastening elements 20, while the lower edge of the superjacent sections will rest upon the upper edge of the next lower section as indicated very clearly in Figure 8.

Prior to the arrangement of the upper sections upon the lower sections, the girts are placed in position and initially the girts are disposed in the manner as shown in Figure 5, 10 wherein the finger 25 is positioned between the spaced fastening elements 10, while the other end of each girt assumes the position shown in Figure 5. It is necessary to employ a special tool for properly positioning the 15 girt across the opposed pairs of spliced bar units and this tool is shown generally at 29 in Figure 5. The tool is specifically described in a co-pending application and therefore a detailed description of the same 20 in the present instance is believed unnecessary.

It will, however, be observed that this tool is adapted to engage one end of the horizontal side of the girt, while another portion of 25 the girt engages with the inner end of one of the fastening elements 10 and by manipulating the lever 30 of the tool, a downward pressure is exerted on the right hand end portion of each girt to properly position the finger 28 between the adjacent fastening elements 10, as shown in Figure 4, and when the girt is thus positioned, the upper ends of the assembled sections will be maintained in a rigid manner for receiving the superjacent 30 sections and the laterally disposed feet 17 will engage with the upper face of the horizontal portion of the respective girts to properly secure the same against upward movement.

40 For the purpose of further securing the assembled parts of the derrick in a rigid manner, I employ the brace rods 31, one of which is shown in detail in Figure 14. A relatively small hook 32 is formed on the lower end 45 of each brace rod for engagement within the respective slot 9, while the upper end of each brace rod is formed with an enlarged hook 33 to engage the diagonally opposed fastening element 14 in the manner as clearly suggested in Figures 1, 4, and 5 of the drawings. 50 These brace rods are arranged on each side of the derrick. Additional reinforcing means shown generally at 34, is associated with the lowermost sections of the corner posts as 55 shown very clearly in Figure 1.

The derrick further includes an improved cap or top structure and to this end a cap member 35 of angular formation has secured to the inner side thereof an angular bracket 36, the bracket being slightly spaced with respect to the respective sides of the cap member 35, in order to accommodate the upper edge portion of the angular bracket or plate 7 carried by the upper ends of the uppermost 60 sections of the corner posts or uprights, and

the lower portion of the angular bracket 36 projects beyond the lower edges of the respective sides of the cap member 35, so as to have abutting engagement with the upper edge of the respective corner posts or uprights as clearly shown in Figure 9. The notches 8 formed in the sides of the angular bracket 7 carried by the uppermost sections receive the fastening means 37, provided for securing the angular bracket 36 to the cap member 35. The top portion of the cap member 35 is illustrated at 38.

The top structure further includes the provision of a pair of opposed headers denoted generally by the reference characters 39 and 80 which headers are adapted for cooperation with the top portions 38 of the cap member 35.

Each of the headers 39 comprises an I beam unit, and as is clearly shown in Figure 10, 85 each end of the top flange 40 is cut away as at 41 for a purpose to be presently described.

A vertically disposed strip 42 is secured on the inner side of the web portion 43, inwardly of the respective ends of each I-shaped beam and the strip 42 is spaced with respect to the web portion 43 by arranging spacing elements around the fastening members 44 that secure the strips 42 to the web portion 43.

95 Each header unit 39 further includes the provision of an elongated angle iron bar 45, the horizontal portion of which underlies the bottom flange 46, of the I beam with the vertical wall of the angle iron bar 45 disposed adjacent the inner edge of the bottom flange 46.

100 The fastening means for the angle iron bar 45 is illustrated at 47 and a spacing element 48 is associated with the fastening means in 105 the manner as clearly shown in Figure 10.

In Figure 13 there is shown the manner in which the angle iron bar 45 is associated with the bottom flange 46 of the I beam header 39.

110 The top portion 38 of the cap member 35 fits between the horizontal wall of the angle iron bar 45 and the bottom face of the flange 46 as suggested very clearly in Figure 9. The top structure further includes the side headers 49, a pair of such members being provided for disposition between the free ends of the opposed headers 39.

115 Each of the headers 49 is of channeled formation and the bottom side of each channel shaped member is cut away at its ends 120 as is also the respective ends of the base portion 50 so that the upper side of the channel shaped member has its extremities projecting beyond the ends of the base portion to provide an ear 51, for a purpose to be presently described.

125 Secured to opposite sides of the base portion 50 of the channel member 49 at each end thereof are the complementary elements 52 and 53, that are so constructed as to provide 130

a slotted housing for receiving the respective strips 42 whereby to provide an interlocking connection between the ends of the headers 49 with the respective ends of the headers 39 and 5 the ears 51 will extend over the upper edges of the uncovered web portion 43, formed by the cut-out portions 41. In this manner, the top structure can be readily and easily assembled or disassembled and when the parts 10 are properly assembled the top structure will be adapted to provide a rigid unit accommodating the drilling mechanism (not shown) in the manner well known in the art.

It will thus be seen from the foregoing description that I have provided a derrick construction that can be quickly assembled and disassembled without putting in or taking out a bolt, and the girts and braces will provide sufficient means for maintaining the sectional uprights or corner posts in assembled relation. Furthermore, by construction a derrick in the manner as shown and above described, the same can be formed of any desirable height and after the well has been 25 drilled the derrick can be dismantled and set up over a new well to be drilled.

A derrick structure of the above mentioned character will not only be strong and durable, but can furthermore be constructed at 30 a very low cost, and also the various adjuncts which are commonly associated with a derrick may be attached thereto in any appropriate manner.

While I have shown the preferred embodiment of my invention, it is to be understood that various changes in the size, shape and arrangement of parts may be resorted to, without departing from the spirit of the invention or the scope of the appended claims.

Having thus described my invention, what I claim as new is:

1. In a derrick, a plurality of superimposed sections forming corner posts, spaced inner and outer angular plate members secured on the upper end of each corner post, the upper portions of said angular plate projecting above the upper end of each corner post, the lower end of the superjacent section having interfitting relation with the angular plate members, the adjacent edges of said superimposed sections having abutting engagement, girts connecting the corner posts of each section together, and means for locking the girts in place, said locking means 50 including an angular plate secured on the outer face of the lower end of the superjacent section adapted to engage the top of the adjacent girt.

2. In a derrick, a plurality of superimposed sections forming corner posts, spaced inner and outer angular plate members secured on the upper end of each corner post, the upper portions of said angular plate projecting above the upper end of each corner post, the lower end of the superjacent sec-

tion having interfitting relation with the angular plate members, the adjacent edges of said superimposed sections having abutting engagement, girts connecting the corner posts of each section together, each girt comprising an angle iron member, the vertical sides thereof being cut out and adapted to be disposed between the spaced plates, and elements extending transversely between the spaced plates for cooperation with the cut out portions of the angle iron girt, and an angular plate secured on the outer face of the lower end of the superjacent section for cooperation with the horizontal side of the adjacent angle iron girt to lock the girt in place.

In testimony whereof I affix my signature.

HOWARD E. WHITE.
